(57) CLAIM

The ornamental design for a shoe, as shown and described.

DESCRIPTION

FIG. 1 is a bottom, lateral side perspective view of a shoe showing the present design;

FIG. 2 is a bottom view thereof; and,

FIG. 3 is a magnified view of the claimed area shown in FIG. 2.

The even-length broken lines shown in the drawings are directed to environment and form no part of the claimed design.

The long and short broken lines are boundary lines, which define bounds of the claimed design. These boundaries do not exist in reality in the article embodying the design. It is understood that the claimed design extends to these boundaries but does not include the boundaries.

1 Claim, 3 Drawing Sheets
